(57) **CLAIM**

The ornamental design for a bowl as shown and described.

DESCRIPTION

1. Bowl

1.1 : Perspective

1.2 : front

This design is related to a bowl; the bowl is essentially conical shape; the base of the bowl is narrow and sharply widens right after the base and provides a wide opening at the top; The outer surface of the bowl has slightly helical slits starting from the base and continuing all the way to the top.
